UNITED STATES PATENT OFFICE.

MAX RUBIN, OF NEW YORK, N. Y.

DESIGN FOR A BELT-CLIP.

SPECIFICATION forming part of Design No. 25,434, dated April 28, 1896.

Application filed March 20, 1896. Serial No. 579,657. Term of patent 7 years.

To all whom it may concern:

Be it known that I, MAX RUBIN, a citizen of the United States, and a resident of the city of New York, in the county of New York and State of New York, have invented a new and original Design for Belt-Clips, of which the following is a specification.

This invention relates to a new and original design for clips for holding belts in place when passed around the waist.

The leading features of my design are a central stem or shank and two downwardly-extending arms on the same and spurs on the ends of said arms.

In the accompanying drawing, forming a part of this specification, a perspective view of my new and original design for belt-clips is shown.

A is the central stem or shank, B B are the arms extending downward from the same and substantially in the same plane as said shank or stem, and C are spurs extending from the free ends of said arms.

Having described my invention, what I claim as new, and desire to secure by Letters Patent, is—

The design for a belt-clip, substantially as herein shown and described.

In testimony that I claim the foregoing as my invention I have signed my name, in presence of two witnesses, this 10th day of February, 1896.

MAX RUBIN.

Witnesses:

OSCAR F. GUNZ,
N. M. FLANNERY.
